(57) CLAIM

The ornamental design for a bowl for water closet, as shown and described.

DESCRIPTION

In a preferred embodiment, the nature of this product is as a plumbing fixture which is primarily useful for receiving the liquid and solid waste of humans.

FIG. 1 is a right, top, front perspective view of a bowl for water closet embodying my new design;

FIG. 2 is a right side elevational view thereof, the left side elevational view being a mirror image of the right side shown;

FIG. 3 is a front elevational view thereof; and,

FIG. 4 is a top plan view thereof.

The broken line representations of holes in FIGS. 1 and 4, and of a lip in FIGS. 1, 2, and 4, are for the purpose of illustration only, and form no part of the claimed design.
